Term of patent 14 years

(Cl. D15—11)

FIG. 1.

FIG. 3.

FIG. 2.

FIGURE 1 is a front perspective view of a restaurant booth seat or similar article showing my new design;

FIG. 2 is an end elevational view taken from the left of FIG. 1., a view from the opposite end (not shown) being the mirror equivalent; and

FIG. 3 is a rear elevational view thereof.

The dominant features of my design reside in those portions shown in full lines on the drawings.

I claim:

The ornamental design for a restaurant booth seat or similar article, substantially as shown and described.
